UNITED STATES PATENT OFFICE.

RAMÓN F. CORDERO, OF RUBIO, VENEZUELA.

COFFEE-SEPARATOR.

No. 844,253.

Specification of Letters Patent.

Patented Feb. 12, 1907.

Application filed July 13, 1906. Serial No. 325,993.

To all whom it may concern:

Be it known that I, RAMÓN F. CORDERO, a citizen of the Republic of Venezuela, and a resident of Rubio, Tachira, Venezuela, have invented a new and Improved Coffee-Separator, of which the following is a full, clear, and exact description.

This invention relates to improvements in separators or sizers for coffee-beans or other material the grains of which are of different sizes or specific gravity, the object being to provide a separator of simple construction by means of which the work may be rapidly carried on, with the complete separation of the material as to size.

I will describe a coffee-separator embodying my invention and then point out the novel features in the appended claims.

Reference is to be had to the accompanying drawings, forming a part of this specification, in which similar characters indicate corresponding parts in all the figures.

Figure 1 shows in plan a separator embodying my invention. Fig. 2 is a section thereof on the line 2 2 of Fig. 4. Fig. 3 is a section on the line 3 3 of Fig. 1, and Fig. 4 is a section on the line 4 4 of Fig. 1.

In carrying out my invention, the separation is made through the agency of water flowing through a plurality of tanks.

Referring to the drawings, 5 designates a tank which may be termed the "receiving-tank," and 6 a tank arranged at right angles to the tank 5 and communicating therewith, and this tank 6 may be termed the "terminal" tank. As is clearly indicated in Figs. 3 and 4, these tanks are slightly inclined, so that the water will flow through the same. A supply-chute 7 leads into the forward end of the tank 5, and the said tank is divided longitudinally between its bottom and top by a fixed board or plate 8, and adjustable on this board or plate is a regulating board or plate 9 to adjust the discharge-opening for the lower portion of the tank. This plate 9 carries a bolt 10, which passes through a slot 11 in the board 8, and by means of this bolt the said plate 9 is held as adjusted. At the opposite end from the inlet the said tank is provided with an outlet-opening 12 for the lower portion of said tank, and this opening is regulated by a gate-valve 13, slideable in ways 14, formed in the side boards of the tank. The said side boards are extended somewhat beyond the gate-valve, and on the top of these extended portions is a cross-plate 15, having

an opening 16, through which a wedge 17 may pass for forcing the gate-valve tightly against the inner walls of said channels 14. It may be stated, however, that other means 60 for securing the gate-valve as adjusted may be employed without departing from the spirit of my invention.

A portion of the water passes from the upper part of the tank 5 to the tank 6, which is 65 provided between its top and bottom with a partition-board 18, the inner end of which is spaced from the outlet of the upper portion of the tank 5, as indicated at 19.

Arranged in the outlet end of the tank 5 is 70 a curved deflecting-plate 20, and a similar deflecting-plate 21 is arranged at the outlet end of the tank 6 for directing material outward through the discharge-opening 22. The end of the lower chamber or portion of the 75 tank 6 has an outlet 23, which is regulated by a gate-valve 24, similar to the gate-valve 13, and the said gate-valve is held in position by means of a wedge 25; but, as before mentioned, other means may be employed. It 80 will be noted that the tanks are arranged at right angles to each other and that the side walls at the discharge end of the lower chamber in the tank 6 are convergent from their inner ends outward, thus providing a somewhat choked outlet.

In the operation, assuming the coffee to be divided into three grades, the several grades are discharged with water into the supply-chute 7, and upon reaching the tank 5 grade 90 No. 1, being the heaviest, will pass to the bottom chamber of said tank 5 and out through the discharge-opening at the end. The other two grades will pass with the water over the boards 9 and 10 to the opening 19, 95 through which the second grade will pass and discharge through the outlet. Then the third grade will pass with the water over the board 18 and discharge through the opening 22. Of course suitable receptacles will be placed 100 to receive the several grades of coffee.

Having thus described my invention, I claim as new and desire to secure by Letters Patent—

1. A separator or sizer, comprising communicating tanks arranged at right angles to each other, one of said tanks being the inlet-tank and the other the terminal tank, a board or plate arranged in the inlet-tank, separating it into upper and lower chambers, 105 an opening being provided between the inlet end of said board or plate and the end of the

tank, an adjustable board for regulating the discharge through the opening of water and material to be separated, the lower chamber of said inlet-tank being provided with a valve-controlled inlet, a board in the terminal tank arranged between the top and bottom, the inner end of said board or plate being spaced from the first tank, a valve-controlled inlet for the lower chamber of the last-named 10 tank, and an outlet for the upper chamber of said last-named tank.

2. A coffee-separator, comprising an inlet-tank and a communicating terminal tank arranged at right angles to the first-named 15 tank, a board or plate arranged in the first-named tank, and having its end spaced from the inlet end of said tank, a sliding valve-plate for adjusting the space, the lower chamber of said first-named tank having an 20 outlet, a gate-valve for said outlet, means for holding the gate-valve as adjusted, a board or plate arranged between the top and bottom of said terminal tank, the end of said board or plate being spaced from the first- 25 named tank, the chamber below said board or plate being provided with an outlet, a gate-valve for said outlet, means for holding said gate-valve as adjusted, and means for directing water with the material to be separated, into said tanks.

3. A coffee-separator, comprising an inlet-tank, and a communicating terminal tank arranged at right angles to the inlet-tank, a board or plate arranged between the top and bottom of the inlet-tank and spaced from the inlet end thereof, the said board or plate dividing said tank into upper and lower chambers, the lower chamber having an out- 35

let-valve for regulating said outlet, a deflector arranged in the upper chamber at the outlet end, a board or plate arranged between the top and bottom of the terminal tank and dividing the same into upper and lower chambers, the lower chamber having an outlet, a valve for said outlet, an outlet 45 for the upper chamber, a deflector at the outlet end of said terminal tank in the upper chamber, and means for directing water and material into the first-named tank.

4. A coffee-separator comprising a pair of 50 inclined tanks arranged at right angles to each other, and communicating, one with the other, each tank being divided into upper and lower chambers, the lower chambers of the tanks having outlets, valves for regulating said outlets, and an incline for discharging water and coffee-beans of various grades, into the first tank, whereby the first or heaviest grade will pass through the water to the lower chamber of said first tank, and discharge therefrom, while the other grades are carried through the upper chamber of the first-named tank, to the second-named tank, whereby the second-grade coffee-beans will pass to the lower chamber of the second tank 60 and discharge therefrom, while the next grade passes through the upper chamber of the second tank and discharges therefrom with the water.

In testimony whereof I have signed my 70 name to this specification in the presence of two subscribing witnesses.

RAMÓN F. CORDERO.
